UNITED STATES PATENT OFFICE

WARREN F. FRASER, OF WESTBORO, MASSACHUSETTS

GRINDING MACHINE

Application filed June 14, 1923. Serial No. 645,319.

This invention relates to improvements in grinding machines.

The object of the invention is to provide a machine particularly adapted for rapidly and accurately grinding large quantities of similarly shaped blanks, said blanks being automatically fed into the machine and accurately positioned and ground to the desired shape and dimensions of the finished article, after which they are automatically released and dropped into a suitable receptacle.

In the machine of this invention the blanks to be ground are preferably placed one above the other in a magazine from which said blanks are taken one at a time and carried forward between the centers of a head-stock and a tail-stock. The blank so carried is then pushed by the tail-stock center into a chuck or other suitable positioning or holding device on the head-stock. A rotary motion is imparted to the chuck and tail-stock spindle, both of which are rotated in unison thereby rotating the blank held therebetween. The grinding wheel rotating at a rapid speed and reciprocating in a direction longitudinally of its axis is then moved into engagement with the blank, the said grinding wheel approaching said blank in a curvilinear path, which, at the point of contact of the grinding wheel and blank, is approximately tangential to the periphery of said blank. The grinding wheel approaches the blank quickly until it engages the same, after which it is fed slowly during the actual grinding operation until it arrives at the limit of its forward feeding movement where it dwells for a sufficient period for the work to be ground to a fine and accurate finish, after which said grinding wheel retreats quickly. The grip of the chuck upon the work is then released and the tail-stock center is withdrawn, thereby permitting the finished article to drop into a suitable receptacle located therebeneath. Another blank is then fed to the grinding instrumentalities and the operation hereinbefore set forth is repeated.

It will be understood that all of the different operations hereinbefore set forth are automatic in their action. The machine is also

provided with the usual apparatus for directing water upon the work during the grinding thereof to keep the same cool, together with an apparatus for maintaining a continuous flow of lubricating oil to certain of the bearings.

The invention consists in the combination and arrangement of parts whereby the above objects and certain other objects hereinafter appearing may be attained as set forth in the following specification and particularly pointed out in the claims thereof.

Referring to the drawings:

Figure 1 is a front elevation of a grinding machine embodying the invention, certain portions thereof being broken away and illustrated in section.

Fig. 2 is a plan view of the machine, certain portions of which are broken away to more clearly illustrate mechanism located therebeneath.

Fig. 3 is an end elevation of the machine as viewed from the right of Fig. 1, the front of the housing for the tail-stock driving mechanism being removed in order to more clearly illustrate said driving mechanism.

Fig. 4 is a central horizontal longitudinal section through the head-stock mechanism.

Fig. 5 is a central horizontal longitudinal section through the tail-stock mechanism.

Fig. 6 is a detail longitudinal section illustrating the floating driving connection to the tail-stock spindle.

Fig. 7 is a sectional elevation illustrating the mechanism for operatively connecting the cam shaft with the work driving shaft to drive the former from the latter.

Fig. 8 is a vertical transverse section taken on the line 8—8 of Fig. 7.

Fig. 9 is a sectional elevation illustrating the cam shaft together with the cams mounted thereon, together with the mechanism for connecting the head-stock cam and the tail-stock cam to the mechanism operated thereby.

Fig. 10 is an end elevation as viewed from the right of Fig. 9 illustrating the tail-stock operating mechanism and a portion of the mechanism for moving the grinding wheel into engagement with the work.

Fig. 11 is a transverse section taken on the

Main driving mechanism

In the drawings, 1 represents the main frame of the machine in which a main driving shaft 2 is journalled in suitable bearings, said shaft being driven by a clutch pulley 3 and driving belt 4. The clutch pulley 3 is operated and controlled by means of a suitable operating lever 5. Fast to the driving shaft 2 is a cone pulley 6 which is connected by a driving belt 7 to a cone pulley 8 fast to a work driving shaft 9 also journalled in suitable bearings provided upon the frame 1.

Head stock mechanism

Formed integral with the main frame 1 is a head-stock bed plate 10, the face of which is preferably inclined at an angle of 45° and mounted upon said bed plate 10 is a head-stock mechanism 11. The head-stock mechanism 11, see Fig. 4, embodies therein a head-stock frame 12 which is mounted to slide longitudinally upon the bed plate 10 and adapted to be secured thereto in the usual well known manner. A spindle 13 is journalled to rotate in a bearing 14 provided in the head-stock frame 12 and said spindle has a sleeve 15 keyed thereto and journalled to rotate in a bearing 16 also provided in the frame 12. The sleeve 15 has a clamp member 17 keyed thereto and the spindle 13, sleeve 15 and clamp member 17 all, therefore, rotate in unison.

The spindle 13 is provided with a bore 18 which extends longitudinally therethrough upon the axis thereof and located within said bore 18 at one end thereof is a spring chuck 19. The spring chuck 19 is formed with an enlarged frustoconical outer end 20 which

is adapted to fit a correspondingly shaped opening 21 at the end of the bore 18, while the outer end of the chuck 19 is provided with a recess 22 in which the work may be inserted and a plurality of radial slots 23 which allow said chuck to grip the end of the work supported therein. A pin 24 fast in the spindle 13 projects into a longitudinal groove 25 provided in the chuck 19, thereby enabling the spindle and chuck to rotate in unison and also enabling the chuck and spindle to be moved longitudinally relatively to each other. The inner end of the chuck 19 is screw-threaded at 26 and has attached thereto a shaft 27 which extends through the spindle 13 upon the axis thereof projecting beyond the rear end of said spindle and having a head portion 28 formed adjacent to its outer end which may be utilized in rotating said shaft 27 relatively to the chuck 19 when it is desired to adjust said chuck within the spindle 13 or entirely remove said chuck from said spindle. Keyed to the shaft 27 is a friction member 29 and the latter is held securely clamped against the clamp member 17 through the medium of another clamp member 30 and screws 31.

Loosely mounted upon the spindle 13 is a clutch member 32 adapted to engage clutch fingers 33 pivoted at 34 upon a collar 35 fastened upon a shouldered portion of the spindle 13. A ring 36 is loosely mounted upon the spindle 13 being interposed between a flanged portion of the sleeve 15 and the collar 35 and said ring is provided with rounded projections 37 which project from one face thereof and contact with the end surface of the sleeve 15 upon opposite sides of the spindle 13, while the ends of the clutch fingers 33 adjacent to the ring 36 are adapted to contact with the side face of the ring 36 when the clutch fingers are located in the position illustrated in Fig. 4. The clutch member 32 is moved longitudinally upon the spindle 13 to engage or release the clutch fingers 33 through the medium of a vertically disposed clutch shifting member 38 which is provided with a forked lower end 39 which partially surrounds said clutch member and is operatively connected thereto. The clutch shifting member 38 is mounted to rock in a suitable bearing provided in a cap 40 provided for the head-stock frame 12, said shifting member being rocked through the medium of an operating arm 41 provided with a handle 42 whereby the head-stock mechanism may be manually operated if it is so desired. The operating arm 41 has a member 43 mounted therein which may be raised through the medium of a finger piece 44 and said member 43 is normally located within a grooved member 45 which is adjustably secured to a lever 46, the latter being pivoted at 47 upon the interior of the frame 1. The lever 46 is rocked through the medium of a cam 48 fast to a cam shaft 49, see Figs. 9

and 11, said cam shaft being journalled in bearings 50 and 51. The lever 46 has a cam roll 52 located at the lower end thereof which is always held in engagement with the periphery of the cam 48 through the medium of a plunger 53 mounted to slide in a bearing member 54, said plunger being forced into contact with said lever through the medium of a spring 55 located within the bearing member 54. When the clutch member 32 is moved toward the left in Fig. 4 into engagement with the clutch fingers 33 the latter are rocked a sufficient distance to cause said fingers to engage the side face of the ring 36 and thus cause the collar 35 to push the spindle 13 toward the right, Fig. 4, and as the shaft 27 and chuck 19 are held against longitudinal movement within said spindle, the conical end surface of the spindle 13 will engage the conical portion of the chuck 19 and cause said chuck to grip the work which has been inserted therein as will be herein-after described.

A rotary motion is imparted to the shaft 27 and the various parts which are rotated in unison therewith through the medium of a sprocket 56 fast to the work driving shaft 9, said sprocket being connected through the medium of a chain 57 with a sprocket 58 fast to a sleeve 59 mounted to rotate in bearings 60 and 61 provided in a housing 62 mounted upon the frame 1 at the left hand end thereof, see Fig. 1. The sleeve 59 has a shaft 63 mounted to slide longitudinally therein and also secured thereto by a key 64 in order that said sleeve and shaft may rotate in unison, and located at one end of said shaft 63 is a coupling 65 which is secured thereto in any desirable manner. The coupling 65 has a recess 66 formed therein into which an end 67 of the shaft 27 projects as illustrated in Fig. 4. The diameter of the recess 66 is substantially greater than the diameter of the end 67 of the shaft 27 thereby enabling said shafts 63 and 27 to be connected to rotate in unison even if said shafts happen to be slightly out of alignment. The end 67 of the shaft 27 is secured to the coupling 65 by a suitable key.

50 Tail-stock mechanism

Formed integral with the main frame 1 is a tail-stock bed plate 68, the face of which is preferably inclined at an angle of 45° and aligns with the head-stock bed plate 10. Mounted upon the bed plate 68 is a tail-stock mechanism 69, see Fig. 5, which embodies therein a tail-stock frame 70 mounted to slide longitudinally upon said bed plate 68 and adapted to be secured thereto in the usual well known manner. A spindle 71 is journalled to rotate in bearings 72 and 73 provided in the tail-stock frame 70 and fast in said spindle and rotatable in unison therewith is a centering pin 74. The longitu-

dinal median lines of the centering pin 74 and chuck 19 are coincident and said pin and chuck co-operate with each other in centering and supporting the work which is located therebetween. The end of the spindle 71 in which the centering pin 74 is located projects through the frame 70 and has a cap 75 fast thereto, a portion thereof surrounding the tubular end of a nut 76 which has screw-threaded engagement with one end 75 of the bearing member 72.

Referring to Figs. 5, 6, 9, 10 and 12, the tail-stock spindle 71 is moved longitudinally within the frame 70 in order to move the centering pin 74 into engagement with the work and to force the latter into the chuck 19 by mechanism as follows:—Mounted upon the shouldered portion of the spindle 71 are collars 77 and 78, both of which are keyed to said spindle and therefore rotate in unison therewith. Loosely mounted upon the shouldered portion of the spindle 71 between the collars 77 and 78 is a washer 79 and a shifting member 80. The collars 77 and 78, washer 79 and shifting member 80 are all prevented from moving longitudinally upon the spindle 71 by a nut 81. A shifting member 82 is mounted to rock in a suitable bearing provided in a cap 83 provided for the tail-stock frame 70, and said shifting member is provided with a forked lower end 84 which partially surrounds the shifting member 80, being operatively connected to the latter through the medium of pins 85 which project into notches 86 provided in the shifting member 80. An operating arm 87 is fast to the shifting member 82 and said arm is provided with a handle 88 whereby the tail-stock mechanism may be manually operated if it is so desired. Fast to the operating arm 87 is a member 89 which projects downwardly into a grooved member 90 which is adjustably fastened to a lever 91 pivoted at 92 upon the interior of the frame 1. A rocking motion is imparted to the lever 91 through the medium of a cam 93 fast to the cam shaft 49, said cam engaging a cam roll 94 fast to the lower end of said lever. A spring 95 acts to always hold the cam roll 94 in engagement with the periphery of the cam 93.

A rotary motion is imparted to the tail-stock spindle 71 and centering pin 74 through the medium of a sprocket 96 fast to the work driving shaft 9 and at the opposite end thereof from that at which the sprocket 56 is located, said sprocket being connected through the medium of a chain 97 with a sprocket 98 fast to a sleeve 99 mounted to rotate in bearings 100 and 101 provided in a housing 102 mounted upon the frame 1 at the right hand end thereof, see Figs. 1 and 3. The sleeve 99 has a shaft 103 mounted to slide longitudinally therein and also secured thereto by a key 104 in order that said sleeve 103

and shaft may rotate in unison and located at one end of said shaft 103 is a coupling 105 which is secured thereto in any desirable manner. The coupling 105 has a recess 106 formed therein into which an end 107 of the tail-stock spindle 71 projects as illustrated in Fig. 6. The diameter of the recess 106 is substantially greater than the diameter at the end 107 of the spindle 71, thereby enabling the spindle 71 and shaft 103 to be connected to rotate in unison even if said spindle and shaft happen to be slightly out of alignment. The end 107 is keyed to the coupling 105 in order that the spindle 71 and shaft 103 may rotate in unison. The shaft 103 is secured to the coupling 105 by being keyed thereto.

A chain tightening device 108 is provided for the chain 97 and embodies an idler sprocket 109 rotatably mounted upon a lever 110 pivoted at 111 to a housing 112 provided for said chain, and said lever is clamped to said housing by a suitable screw 113.

Cam shaft driving mechanism

25 The mechanism for driving the cam shaft 49 at a greatly reduced speed from the work driving shaft 9 and for disconnecting the former from the latter to prevent the operation of the cam shaft is as follows:—

30 Referring to Figs. 7 and 8, the work driving shaft 9 has a spiral gear 114 fast thereto which meshes with and rotates a spiral gear 115 fast to a sleeve 116 mounted to rotate loosely upon a countershaft 117 journaled 35 to rotate in suitable bearings provided in a casing 118, the latter being secured to the exterior of the frame 1. A gear 119 fast to the shaft 117 meshes with and rotates a gear 120 fast to a countershaft 121 journaled to 40 rotate in bearings provided in the casing 118. Another gear 122 fast to a countershaft 121 meshes with and rotates a gear 123 fast to a countershaft 124 also journaled to rotate in bearings provided in the casing 118. A worm 45 125 fast to the countershaft 124 meshes with and rotates a worm gear 126 fast to the cam shaft 49. The countershaft 124 is provided with a squared end 127 to which a suitable crank may be connected thereby enabling the 50 cam shaft to be manually operated if it is so desired.

Also fast to the sleeve 116 and rotatable therewith is a clutch member 128. Another clutch member 129 is keyed to the counter-shaft 117 and is also adapted to slide longitudinally upon said shaft into and out of engagement with the clutch member 128, the said clutch member 129 receiving its longitudinal movement from a forked arm 130 55 fast to a rock shaft 131 mounted in the casing 118. An arm 132 also fast to said rock shaft 131 has a connecting rod 133 attached thereto which extends to and is connected with an arm 134 fast to a rock shaft 135 mounted 60 in the frame 1 and said rock shaft has an

operating handle 136 attached thereto at the front of the machine, see Fig. 1, and located in a convenient position to be manipulated by the attendant.

Work feeding mechanism

The mechanism for holding the work which consists of blanks and for feeding said blanks one at a time into position to be gripped between the head-stock and tail-stock is as follows:—Referring to Figs. 2, 70 9 and 13, the blanks A are preferably supported one above the other in a magazine 137 which embodies therein a pair of oppositely disposed grooved guide members 138 into which the opposite end of the blanks project. The guide members 138 are supported upon brackets 139 which are adjustably secured to a cross bar 140 forming a part of the guard 141. The lowermost blank A in the magazine rests upon supports 142 which are pivoted at 143 to brackets 144 which are adjustably secured to an oscillatory frame 145. Each support 142 may be adjusted to raise or lower the upper surface thereof through the 75 medium of a screw 146, the lower end of which engages a lug 147 formed integral with the bracket 144. After each support 142 is correctly positioned relatively to its bracket 144, said support is clamped to said bracket 80 through the medium of a clamp screw 148. Each support 142 is provided with projections 149 upon which the blanks A rest and between said projections a latch 150 is pivoted at 151, said latch co-operating with its support 142 to form a pocket into which the blanks may fall one at a time as the supports 142 oscillate beneath the pile of blanks. The lower end of each latch 150 engages a 85 spring pin 152 slidably mounted within the support 142 and after the blank A which is located within the pocket at the front of said support has been gripped between the chuck 19 and centering pin 74 the supports 142 move 90 rearwardly, the latches 150 yielding beneath the blank A and forcing the spring pins 152 inwardly. After the latches 150 have passed beneath the blank A the spring pins will immediately force the latches upwardly to 95 again form the pockets to receive the next 100 blank. 105

The oscillatory frame 145 embodies therein a pair of downwardly projecting arms 153 formed integral with a hub 154 which is clamped to a shaft 155 mounted to rock in brackets 156 supported upon the frame 1. At one end of the rock shaft 155 an arm 157 is fast, said arm having a cam roll 158 located at its lower end which engages a cam 159 fast to the cam shaft 49. A spring 160, 110 one end of which is fastened to the arm 157, and the other end of which is fastened to a screw 161 acts to always pull the lower end of the arm 157 toward the cam 159 and hold the cam roll 158 in engagement with the 115 pe- 120 125 130 135 140 145 150 155 160 165

riphery of said cam. The tension of the spring 160 is adjusted through the medium of a nut 162 with which the screw 163 has engagement, said nut 162 being rotatably mounted in a plate 163' fast to the front of the frame 1. The amount of throw given to the frame 145 may be varied by a pin 164 which is adjustably mounted in the plate 163', said pin acting as a stop to limit the forward movement of the slide 142.

Grinding mechanism

The mechanism for grinding the blanks A to a finished dimension is as follows:—referring particularly to Figs. 14 to 19 inclusive, the frame 1 has a bed plate 165 formed integral therewith upon which a slide 166 is mounted, said slide being pivoted at 167 to rock in a horizontal plane upon the upper surface of said bed plate to which it is clamped by a plurality of screws 168, said screws passing through suitable slots provided in said slide, see Fig. 14. A bracket 169 is fast to the slide 166 and has a stud 170 mounted therein. Another bracket 171 is fast to the frame 1 and has a stud 172 mounted therein. A connecting rod 173 extends between the stud 170 and the stud 172, being fast at one end in the stud 170 and being slidable within the stud 172. Nuts 174 and 175 have screw-threaded engagement with the connecting rod 173 and are located upon the opposite sides of the stud 172 and when it is desired to rock the slide 166 upon the bed plate 165 to vary the angular relation between the face of the grinding wheel and the work, the screws 168 are first loosened and the nuts 174 and 175 are rotated in the proper direction to move the slide 166 as required. A scale 176 is fastened to the side of the slide 166 at one of the corners of said slide, said scale being curved and concentric with the pivot 167 and said scale is provided with graduations 177 which co-operate with an indicator 178 in indicating the amount of movement imparted to said slide.

A carriage 179 is mounted to slide upon ways 180 and 181 formed upon the slide 166 and said carriage is moved relatively to said slide to position the face of the grinding wheel relatively to the work which is necessary every time that the dimensions of the blanks are changed, or after the face of the grinding wheel has been redressed through the medium of a worm 182 fast to a shaft 183 journalled to rotate in a bearing 184 fast to the carriage 179. The worm 182 engages a plate 185 fast to the slide 166, said plate, in effect, constituting a stationary nut which is provided with teeth 186 with which the periphery of the worm 182 engages. The shaft 183 has a gear 187 fastened thereto which meshes with and is rotated by a gear 188 loosely mounted upon a stud 189 non-rotat-

ably mounted in the carriage 179. The gear 188 meshes with and is driven by a pinion 190 fast to a shaft 191 mounted to rotate in bearings 192 and 193 located within a tube 194, said tube being clamped in arms 195 and 196 which project upwardly from the carriage 179. The shaft 191 is rotated through the medium of a hand wheel 197, and an index finger 198 is clamped to the tube 194 and registers with graduations 199 provided upon the periphery of the hand wheel 197.

Mounted upon the carriage 179 is a rocking member 200 which is provided with trunnions 201 and 202 located in bearings 203 and 204 respectively formed upon said carriage. The bearings 203 and 204 also embody therein caps 205 and 206 respectively. Located within the rocking member 200 and secured therein in any suitable manner are split bearings 207 and 208 in which a shaft 209 is journalled to rotate, and fast to said shaft at one end thereof is a grinding wheel 210. The axis of the shaft 209 is eccentrically disposed relatively to the axis of the rocking member 200, see Fig. 17, and this particular construction and relationship between the axes of the shaft 209 and the rocking member 200 constitutes one of the principal features of this invention. The shaft 209 is rotated through the medium of a pulley 211 fast there to which, in turn, is rotated through the medium of a belt 212 which is driven through the medium of a pulley 213 fast to the main driving shaft 2, see Fig. 15. The belt 212 in passing from the driving pulley 213 extends over an idler pulley 214 mounted upon a shaft 215 mounted in a bracket 225 fast to the frame 1 and also over a take-up pulley 216 mounted upon a shaft 217, the latter being mounted in a lever 218 pivoted at 219 upon the bracket 225. The take-up pulley 216 is held in yielding engagement with the belt 212 through the medium of a spring 220, one end of which is secured to a bracket 221 attached to the frame 1, the other end of said spring being attached to an adjusting screw 222 mounted in a block 223 fast to the lever 218 and the tension upon the spring 220 is varied by manipulating an adjusting nut 224 which has screw-threaded engagement with the screw 222.

The rocking member 200 is rocked within the carriage 179 to move the grinding wheel 210 from its normal position as represented in dotted lines, Fig. 17 through a curvilinear path into engagement with the work A at 120 which time it assumes the position illustrated in full lines, Fig. 17 by mechanism as follows:—Rigidly fastened to the outer end face of the trunnion 202 of the rocking member 200 is an arm 226, see Fig. 16, upon which a block 227 is mounted to swivel through the medium of a stud 228. The block 227 projects into a grooved member 229 which is adjustably mounted upon a screw-threaded end 230 of a vertically disposed rod 231, the 125

- latter being mounted in a bearing bracket 232 fast at the end of the frame 1. A recess 233 is provided at the lower end of the rod 231 and located within said recess is a member 234 which is normally forced upwardly 5 against the end of the recess 233 through the medium of a spring 235, the opposite end of said spring contacting with the inner end of a screw plug 236. The outer end of the screw plug 236 rests upon an adjusting screw 237 mounted in the bracket 232. The rod 231 is raised and lowered through the medium of a lever 238 pivoted at 239 upon the bearing bracket 232 and said lever has an end portion 240 detachably secured thereto which projects into a slot 241 formed in the member 234. The opposite end of the lever 238 has a cam roll 242 mounted thereon which projects into a groove 243 of a cam 244 fast to the cam shaft 49.
- 10 The cam 244 imparts a rocking movement to the lever 238 which, in turn, transmits a reciprocatory motion to the rod 231, which, in turn, rocks the member 200 through the medium of the arm 226, thereby lifting the grinding wheel 210 from the dotted line position illustrated in Fig. 17 and the periphery of said grinding wheel travels upwardly in a curvilinear path, the radius of which is greater than the radius of the grinding wheel, 15 until the axes of the work A, grinding wheel shaft 209 and rocking member 200 are all located in the same plane also as illustrated in said Fig. 17. At this time the curvilinear path through which the periphery of the grinding wheel has travelled is approximately tangential to the periphery of the work at its point of contact with said work.
- 20 The groove 243 of the cam 244 is so constructed that the grinding wheel approaches the work quickly until it is approximately in engagement therewith, after which said grinding wheel is fed slowly during the grinding operation until it arrives at the limit of its upward movement which position is illustrated in Fig. 17, where it dwells for a short period during which time the work is ground to a fine and accurate finish, after which the grinding wheel drops quickly to its initial position.
- 25 The mechanism for imparting a reciprocatory movement to the grinding wheel longitudinally of its axis is as follows:—Referring particularly to Figs. 16, 17 and 18, a shaft 245 is journalled to rotate in bearings 246 and 247 formed in the carriage 179 and cap 206 and said shaft has a shouldered portion 248 formed integral therewith which is also eccentrically disposed relatively to the main portion of said shaft. A block 249 is loosely mounted upon the eccentric portion 248, said block being located between ways 250 formed in the trunnion 202 of the rocking member 200, said ways being in sliding engagement 30 with said block. A clutch member 251 is keyed to the shaft 245 and is also adapted to slide longitudinally thereon into engagement with a clutch member 252 which is loosely mounted upon the shaft 245. A worm gear 253 is fast to a clutch member 252 and said worm gear is rotated through the medium of a worm 254 fast to a shaft 255 journalled to rotate in suitable bearings provided in the carriage 179. The shaft 255 is rotated through the medium of a pulley 256 which is fast thereto, said pulley being rotated through the medium of a belt 257 from a pulley 258 fast to the main driving shaft 2.
- 35 The clutch member 251 is moved into and out of engagement with the clutch member 252 through the medium of a clutch shifting member 259 fast to a shaft 260 mounted in the carriage 179 and said shaft is rocked through the medium of an operating handle 261 fast to said shaft and located at a convenient position at one end of the machine.
- 40 A cover plate 262 is located above that portion of the rocking member 200 which is located between the caps 205 and 206, see Figs 2 and 19, and a guard 263 is provided for the grinding wheel 210. The work A after it has been ground is released from between the head-stock and tail-stock mechanisms and drops into a suitable receptacle 264, the bottom of which slopes forwardly thereby enabling said work to slide or roll to a convenient location at the front of the machine from which position it may be easily removed.
- 45 *General operation*
- 50 Assuming that the machine is in a position where a blank has just been ground and dropped into the receptacle 264 and the machine is ready to receive another unfinished blank in order that the same may be ground, the operator starts the machine by moving the operating handle 136 in the proper direction to throw the clutch member 129 into engagement with the clutch member 128, thereby causing the cam shaft 49 to be rotated from the work driving shaft 9 through the medium of the gearing illustrated in Figs. 7 and 8. It will be understood that the work driving shaft 9 is rotating continuously, being driven from the main driving shaft and that the head-stock spindle 13 and chuck 19 and tail-stock spindle 71 and centering pin 74 are rotating continuously in unison, being driven from the work driving shaft 9, while the grinding wheel 210 is rotating continuously, being driven from the main driving shaft 2.
- 55 As soon as the cam shaft 49 commences to rotate, the cam 159 will operate the mechanism to move the lowermost blank A in the magazine 137 forwardly into position between the head-stock and tail-stock mechanisms. The cam 93 will then operate the mechanism to move the tail-stock spindle 71 longitudinally causing the centering pin 74 to engage the blank A and push the same into 60

the chuck 19. The cam 48 will then operate the mechanism to cause the chuck 19 to grip the blank A, whereupon said blank will immediately begin to rotate in unison with the head-stock and tail-stock spindles. The cam 159 will then return the work supports 142 to their initial position and allowing another blank to drop into the pocket formed by the projections 149 and latches 150.

10 During the time that the head-stock and tail-stock mechanisms are gripping and centering the blank, the cam 244 is feeding the grinding wheel 210 quickly towards said blank, the said grinding wheel travelling in a 15 curvilinear path as it approaches the blank. As soon as the grinding wheel engages the blank, the cam 244 is so designed that the feeding movement of the grinding wheel into the work is very slow until the limit of this 20 feeding operation is reached, the grinding wheel dwelling in this position for a period while the work is receiving its final grinding. During all this time the grinding wheel is reciprocating in a direction longitudinally of 25 its axis, although this mechanism may be thrown out of operation if it is so desired through the medium of the operating handle 261. As soon as the grinding of the blank is completed and while the grinding wheel is 30 withdrawing, the tail-stock spindle 71 is withdrawn and the chuck 19 releases the blank which falls into the receptacle 264 located therebeneath.

After the grinding wheel has been returned 35 to its initial position and the finished article ejected from the machine as described, the operations hereinbefore set forth are repeated on another blank and thus the operation continues until the machine is stopped 40 by the operator, either by shifting the operating handle 136, thereby preventing the rotation of the cam shaft 49, or operating the clutch lever 5 and preventing the rotation of the main driving shaft.

45 If the character of the work is such that it is necessary to adjust the grinding wheel 210 so that the face of said grinding wheel is located at an angle to the axis of the work, the same is accomplished by loosening the 50 screws 168 which fasten the slide 166 to the frame 1 and manipulating the adjusting nuts 174 and 175 until the face of the grinding wheel is positioned as desired relatively to the work.

55 Whenever it is necessary to adjust the position of the grinding wheel laterally of the work which is necessary after the grinding wheel has been redressed, the same is accomplished by rotating the hand wheel 197, 60 thereby moving the carriage 179 upon which the grinding wheel is mounted, bodily toward the work.

It will be understood that in some classes 65 of work a gripping chuck is not required, the work being driven in some cases by the head-

stock and tail-stock centers by friction alone, and I do not wish to be understood as limiting my invention to any specific means for holding the work and rotating the same.

I claim:

1. A grinding machine comprising, in combination, a work member, means to support and rotate said work member, a grinding member, means to support and rotate said grinding member and means to cause one of 70 said members to approach and engage the other of said members in a path approximately tangential to the point of contact of said grinding wheel and work.

2. A grinding machine comprising, in combination, means to support and rotate work, means to feed said work to said supporting means, a grinding member, means to support and rotate said grinding member and means to cause said grinding member to approach 80 and engage said work in a path approximately tangential to the point of contact of said grinding member and work.

3. A grinding machine comprising, in combination, means to support and rotate work, means to feed said work to said supporting means, a grinding member, means to support and rotate said grinding member, means to cause said grinding member to approach, engage and withdraw from said work 90 in a path approximately tangential to the point of contact of said grinding member and work and means to release said work from said supporting means.

4. A grinding machine comprising, in combination, means to support and rotate work, a magazine adapted to hold a plurality of work blanks, means to feed said work blanks one at a time from said magazine to said supporting means, a grinding member, means to support and rotate said grinding member, means to cause said grinding member to approach, engage and withdraw from said work in a path approximately tangential to the point of contact of said grinding member and work 100 and means to release said work from said supporting means.

5. A grinding machine comprising, in combination, means to rotatably support work at the opposite ends thereof, means to feed said work to said supporting means, means including said supporting means to rotate said work, a rotary grinding member, means to cause said grinding member to approach, engage and withdraw from said work in a path approximately tangential to the point of contact of said grinding member and work 115 and means to release said work from said supporting means.

6. A grinding machine comprising, in combination, means to grip work at one end thereof, means to center said work at the other end thereof, means to feed said work to said gripping means and centering means, means to 120

rotate said work, a rotary grinding member and means to move said grinding member through a curvilinear path into and out of engagement with said work, said path being approximately tangential to the point of contact of said grinding member and work.

7. A grinding machine comprising, in combination, means to grip work at one end thereof, means to center said work at the other end thereof, means to feed said work to said gripping means and centering means, means to rotate said work, a rotary grinding member, means to position said grinding member so as to vary the angular relation between the face of said grinding member and said work and means to move said grinding member through a curvilinear path into and out of engagement with said work.

8. A grinding machine comprising, in combination, means to grip work at one end thereof, means to center and support said work at the other end thereof, a magazine adapted to hold a plurality of work blanks, means to feed said work blanks one at a time to said gripping means and centering means, means to rotate said gripping means, means to rotate said centering means, a rotary grinding member and means to cause said grinding member to approach, engage and withdraw from said work in a path approximately tangential to the point of contact of said grinding member and work.

9. A grinding machine comprising, in combination a head-stock and a tail-stock adapted to support and rotate work, a magazine embodying therein a plurality of supports adapted to support a column of work blanks, means to actuate said supports to carry said work blanks one at a time from said column to said head-stock and tail-stock, a rotary grinding member and means to move said grinding member through a curvilinear path into engagement with a work blank held by said head-stock and tail-stock, said path being approximately tangential to the point of contact of said grinding member and work.

10. A grinding machine comprising, in combination, a head-stock and a tail-stock adapted to support and rotate work, a magazine embodying therein a plurality of supports adapted to support a column of work blanks, a frame upon which said supports are mounted, means to rock said frame to carry said work blanks one at a time from said column to said head-stock and tail-stock, a rotary grinding member and means to move said grinding member through a curvilinear path into engagement with said work blank held by said tail-stock and head-stock, said path being approximately tangentially to the point of contact of said grinding member and work.

11. A grinding machine comprising, in combination, means to grip work at one end thereof, means to center and support said

work at the other end thereof, a magazine adapted to hold a plurality of work blanks, means to feed said work blanks one at a time into alignment with said gripping means and centering means, means to move said centering means toward said gripping means whereby the work held by said feeding means may be inserted in said gripping means, means to rotate said gripping means whereby a rotary motion may be imparted to said work, a rotary grinding member and means to cause said grinding member to approach, engage and withdraw from said work in a path approximately tangential to the point of contact of said grinding member and work.

12. A grinding machine comprising, in combination, means to grip work at one end thereof, means to center and support said work at the other end thereof, a magazine adapted to hold a plurality of work blanks, means to feed said work blanks one at a time into alignment with said gripping means and centering means, means to move said centering means toward said gripping means whereby the work held by said feeding means may be inserted in said gripping means, means to rotate said gripping means whereby a rotary motion may be imparted to said work, a rotary grinding member, means to position said grinding member so as to vary the angular relation between the face of said grinding member and said work and means to move said grinding member through a curvilinear path into and out of engagement with said work, said path being approximately tangential to the point of contact of said grinding member and work.

13. A grinding machine comprising, in combination, means to grip work at one end thereof, means to center and support said work at the other end thereof, a magazine adapted to hold a plurality of work blanks, means to feed said work blanks one at a time into alignment with said gripping means and centering means, means to move said centering means toward said gripping means whereby the work held by said feeding means may be inserted in said gripping means, means to rotate said gripping means whereby a rotary motion may be imparted to said work, a rotary grinding member, means to position said grinding member so as to vary the angular relation between the face of said grinding member and said work, means to move said grinding member through a curvilinear path into and out of engagement with said work, said path being approximately tangential to the point of contact of said grinding member and work and means to impart a reciprocatory motion to said grinding member longitudinally of its axis.

14. A grinding machine comprising, in combination, means to grip work at one end thereof, means to center and support said work at the other end thereof, a magazine

grinding wheel into and out of engagement with said work.

22. A grinding machine comprising, in combination, a head-stock embodying therein a chuck, a tail-stock embodying therein a centering pin, a magazine adapted to hold a plurality of work blanks, means to feed said work blanks one at a time into alignment with said chuck and centering pin, means to cause said centering pin to move said work into said chuck, means to cause said chuck to grip said work, means to rotate said chuck, means to rotate said centering pin, a rocking member, a shaft rotatably mounted within said rocking member eccentric to the axis thereof, a grinding wheel fast to said shaft, means to rotate said shaft and means to impart a rocking movement to said rocking member and thereby move said grinding wheel into and out of engagement with said work.

23. A grinding machine comprising, in combination, a head-stock embodying therein a chuck, a tail-stock embodying therein a centering pin, a magazine adapted to hold a plurality of work blanks, means to feed said work blanks one at a time into alignment with said chuck and centering pin, means to cause said centering pin to move said work into said chuck, means to cause said chuck to grip said work, means to rotate said chuck, means to rotate said centering pin, a slide, a carriage mounted upon said slide, a locking member mounted upon said carriage, a shaft rotatably mounted within said rocking member eccentric to the axis thereof, a grinding wheel fast to said shaft, means to rotate said shaft, means to position said slide to vary the angular relation between the face of said grinding wheel and said work, means to impart a rocking movement to said rocking member and thereby move said grinding wheel into and out of engagement with said work.

24. A grinding machine comprising, in combination, a head-stock embodying therein a chuck, a tail-stock embodying therein a centering pin, a magazine adapted to hold a plurality of work blanks, means to feed said work blanks one at a time into alignment with said chuck and centering pin, means to cause said centering pin to move said work into said chuck, means to cause said chuck to grip said work, means to rotate said chuck, means to rotate said centering pin, a slide, a carriage mounted upon said slide, a rocking member mounted upon said carriage, a shaft rotatably mounted within said rocking member eccentric to the axis thereof, a grinding wheel fast to said shaft, means to rotate said shaft, means to position said slide to vary the angular relation between the face of said grinding wheel and said work, means to move said carriage upon said slide to position said grinding wheel laterally of said work and means to impart a rocking movement to said rocking

member and thereby move said grinding wheel into and out of engagement with said work.

25. A grinding machine comprising, in combination, a head-stock embodying therein a chuck, a tail-stock embodying therein a centering pin, a magazine adapted to hold a plurality of work blanks, means to feed said work blanks one at a time into alignment with said chuck and centering pin, means to cause said centering pin to move said work into said chuck, means to cause said chuck to grip said work, means to rotate said chuck, means to rotate said centering pin, a slide, a carriage mounted upon said slide, a locking member mounted upon said carriage, a shaft rotatably mounted within said rocking member eccentric to the axis thereof, a grinding wheel fast to said shaft, means to rotate said shaft, means to position said slide to vary the angular relation between the face of said grinding wheel and said work, means to move said carriage upon said slide to position said grinding wheel laterally of said work, means to impart a rocking movement to said rocking member and thereby move said grinding wheel into and out of engagement with said work and means to impart a reciprocatory motion to said rocking member longitudinally of its axis.

26. In a machine for grinding the bearing surface of rollers for roller bearings and the like, means for rotatably holding a roller, a grinding wheel, and means for moving said grinding wheel in a substantially tangential path with respect to the bearing surface of the roller.

27. In a device of the kind set forth, means for rotatably holding a conical roller for roller bearings, a pivotally mounted arm, a grinding wheel mounted at the end of said arm for grinding the bearing surface of said roller, and means for swinging said arm so that the axis of said grinding wheel traverses the straight line passing the axis of the work and the pivot of said arm.

28. In a grinding machine adapted to grind the bearing surface of rollers for roller bearings, means for rotatably supporting a roller and for positively rotating the same, a grinding wheel, means for moving said grinding wheel in a path substantially tangential with respect to the bearing surface of the roller, the path of movement of the axis of said grinding wheel traversing a line perpendicular to the direction of its motion and passing through the axis of the roller.

29. A process for grinding the bearing surface of rollers for roller bearings and the like that comprises swinging a grinding wheel about a pivot in a path such that the axis of the grinding wheel traverses a straight line that passes through the axis of the work and the pivot about which said grinding wheel is swung.

30. A grinding machine comprising, in combination, means to support and rotate work, a rocking member, a shaft mounted within said rocking member eccentric to the axis thereof, a grinding wheel mounted upon said shaft, means to rotate said grinding wheel, and means to impart a rocking movement to said rocking member and thereby move said grinding wheel into engagement with said work.

31. A grinding machine comprising, in combination, a frame, oppositely disposed rotatable work supporting means adjustable longitudinally thereof upon the upper part of said frame, a rotatable grinding member, a power shaft rotatably mounted upon the lower part of said frame, driving means connecting said power shaft and said work supporting means, said driving means being in fixed position relatively to the frame, and slideable driving connections between said driving means and said work supporting means.

32. A grinding machine comprising, in combination, a frame, oppositely disposed rotatable work supporting means adjustable longitudinally thereof upon the upper part of said frame, a slide mounted on said frame, a rotatable grinding member upon said slide, a power shaft rotatably mounted upon the lower part of said frame, driving means connecting said power shaft and said work supporting means, said driving means being in fixed position relatively to the frame, slideable driving connections between said driving means and said work supporting means, and means to adjust said slide to vary the angular relation between the operative face of said grinding member and the work.

40. In testimony whereof I have hereunto set my hand.

WARREN F. FRASER.
